SAND MULLING AND AERATING MACHINE

William H. Nicholls, Roslyn, N. Y.; William H. Nicholls, Jr., administrator of William H. Nicholls, deceased, assignor, by mesne assignments, to Herbert S. Simpson, Chicago, Ill.

Application November 25, 1935, Serial No. 51,540

2 Claims. (Cl. 83—45)

This invention is an improvement over the disclosure in my Patent No. 1,636,384 granted July 19th, 1927.

The invention relates to foundry equipment 5 and has particular reference to means for preparing the sand used in forming molds.

The principal object of the invention, generally stated, is to provide a highly efficient, continuously operating apparatus for mulling the sand, finely dividing it and discharging it into the air in a diffused state so as to effect aeration.

It is well known that machines of this general type embody rollers which are driven over the bottom of the mulling basin for the purpose of 15 intermingling clay with the sand and for crushing or crumbling any lumps of sand or sand and clay and working or what might be called kneading the sand mixture so that the entire mass thereof will be thoroughly broken up and reduced 20 to a condition of fineness appropriate for use in forming molds. However, it has been found that the abrading action on the bottom of the mulling basin results in serious wear, even to such an extent that destruction and consequent replacement 25 is necessary in a comparatively short time.

It is with the above facts in view that I have devised the present invention which contemplates maintaining what might be called a cushion of sand which remains stationary while the rollers 30 travel in their orbits and which therefore does not produce any friction or abrasion on the bottom of the basin, the life of the machine being consequently greatly prolonged.

A more specific object of the invention is to 35 provide a mulling machine embodying rollers travelling in circular orbits, at least one of the rollers having its periphery either circumferentially or transversely grooved so that the roller will have a greatly increased crumbling or mull- 40 ing action on the sand.

Another specific object of the invention, and one of tremendous importance, is to provide a mulling machine in which the bottom of the basin is formed with a series of concentric grooves with- 45 in which the sand or mixture will pack and acquire a rock-like hardness, the sand, moreover, according to its natural tendency, projecting above the top surface of the basin bottom and consequently defining ridges between which loose 50 sand is entrapped and therefore held stationary, all the friction and abrasive action therefore taking place upon the sand itself instead of on the bottom of the basin.

The invention further contemplates the provi- 55 sion in a machine of this character of means for

separating the sand finely after it has been milled and discharging it into the air in a diffused state so as to effect aeration, these features being, however, disclosed in said prior patent.

An additional object of the present invention is 5 to provide a machine of the character set forth and for the purpose specified which will be not only continuous and efficient in its operation but which will be simple and inexpensive to make, easy to use, positive in action, and a general im- 10 provement in the art.

To the attainment of the foregoing and other objects and advantages, the invention preferably consists in the details of construction and the arrangement and combination of parts to be here- 15 inafter more fully described and claimed, and illustrated in the accompanying drawings in which:

Figure 1 is a plan view of the device with the shell in section, 20

Figure 2 is a central longitudinal sectional view through the machine, the view being taken on the line 2—2 of Figure 1,

Figure 3 is a side elevation of a modified form of roller, 25

Figure 4 is an edge view thereof,

Figure 5 is a detail perspective view of sweeper means for discharging the sand from the mulling basin,

Figure 6 is a fragmentary enlarged detail sec- 30 tion illustrating the sand packed in the grooves and showing the action.

Referring more particularly to the drawings, the numeral 1 designates the base of the machine above which is supported, by legs 2, a mull- 35 ing basin indicated as a whole by the numeral 3 and including a bottom 4 preferably provided with an upstanding peripheral flange 5 located outwardly of and constituting retaining means for a cylindrical shell 6 which defines the side wall 40 of the basin. Engaged upon the upper edge of this shell is a funnel member or hopper 7 having a central opening 8 through which sand is fed into the basin.

The bottom 4 is formed or otherwise provided 45 centrally with a bearing 9 here represented as extending above and also below the bottom. Journaled through this bearing is a shaft 10 equipped at its lower end with a relatively large bevel gear 11 and having an enlarged portion 12 50 near its upper end located above the bearing 9. This enlarged portion 12 is formed with diametri- cally opposite flattened areas 13 and is straddled by U-shaped yokes 14, preferably lapped as shown in Figure 1, and which are pivotally mounted as 55

by a pin or bolt 15 so as to have limited vertical swinging movement. These yokes carry shafts 16, upon one of which is journaled a roller 17 and upon the other of which is journaled a roller 18. 5 The exact mounting for these rollers may be considered more or less immaterial but in the present instance they are represented as held in place by nuts 19 screwed onto the threaded ends of the shafts 16. Fixed with respect to the shafts 16 10 are collars 20 received within recesses 21 and formed with grooves 22 filled with appropriate packing for the purpose of excluding the sand from the bearing surfaces within the rollers. The lapped relation of the yokes 14 is clearly shown in 15 Figure 1 and the purpose is to offset them relatively so that the shafts 16 will be out of diametric alignment so that the rollers shall have a sweeping action, the eccentric mounting tending to cause the sand mixture to be gradually moved 20 outwardly toward the discharge opening of the basin.

It is a very important feature of the present invention that one or even both of the rollers should be corrugated or formed with alternating 25 ridges and grooves. In the present instance only the roller 18 is disclosed as grooved, the other being smooth, but it will be understood that both can be grooved if preferred. In Figures 1 and 2 the roller 18 is shown as having its grooves 23 30 extending peripherally but it is a possibility to resort to the construction shown in Figures 3 and 4 wherein I have shown a roller 24, corresponding to the roller 18 but having its grooves 25 extending transversely instead of circumferentially. It 35 is within the purview of the invention to substitute the roller 24 for the roller 18. Regardless of which type of roller is used it is another important feature of the invention that the top surface of the basin bottom 4 is formed with a series 40 of concentric grooves 26 which will of course be filled by the sand charged into the basin through the hopper opening 8. The theory is, and practice has proved its correctness, that the sand or mixture filling the grooves 26 will be packed by 45 the rotating rollers to a rock-like hardness. Moreover the sand filling the grooves will project above them and thus define circular ridges between which a thin layer of loose sand will be entrapped and maintained substantially stationary so as not to abrade the bottom 4 of the basin. 50

It will be observed that the shafts 16 are of unequal length so that the grooved roller 18 will travel over the inner portion of the basin bottom while the roller 17 travels over the outer portion, 55 the paths of the two rollers being staggered. It might also be mentioned, in passing, that any desired means may be employed for effecting lubrication within the rollers and that any desired means may be provided for excluding sand from bearing areas. However, these are mere mechanical details which do not enter into the essence 60 of the invention and are consequently not illustrated.

The upper end of the shaft 10 is represented as 65 reduced and threaded as at 28. Supported upon the shoulder formed by the enlarged portion 12 of the shaft at the base of said reduced end is a sand pushing or sweeping element 29, shown in detail in Figure 5. This device is formed with a 70 central hub portion 30 apertured to receive the reduced threaded end of the shaft 10 and recessed at its underside to fit snugly over the upper end of the shaft enlargement 12 with its flat sides 13. Arms 31 are provided on the hub 30 and extend 75 outwardly therefrom in opposite directions. Se-

cured to the arms 31 are outwardly extending arms 32 each formed with a plurality of downwardly extending sweeping or agitating members 33. The hub 30 is secured to the upper end of the shaft 10 by a nut 34 threaded onto the reduced extension 28 and the sweeper is so located that the arms 32 thereof are disposed at substantially right angles to the axes of the mulling rollers. The outermost sweeping members 33 of the arms 32 are disposed in close proximity to the bottom and outer side wall 6 of the mulling basin. When the shaft 10 is rotated, the rollers will be revolved in a circular orbit but eccentric to the shaft and the outermost sand sweeping members 33 will be turned with the rollers but in a concentric circular orbit outwardly of the roller orbit so that sand within the basin will be worked toward the outside wall 6. The bottom of the basin is formed with a discharge opening 35 located outwardly of the rollers and in the path of the outermost sweepers 33. The agitating members 33 located intermediate the lengths of the two arms 32 are staggered, that is, the members upon the two different arms are located unequal distances from the shaft 10. The agitating members upon one arm will therefore move in concentric paths located between the concentric paths of the members supported by the other arm. The members are thus adapted to agitate the sand over substantially the entire bottom area of the basin after the rollers have passed over it.

Located at one side of the mulling basin in a position to receive the sand as it is discharged through the opening 35 is a cylindrical sand-diffusing drum 36. This drum is rotatably mounted between upstanding side wall members 37 supported by the base 1 and arranged adjacent the ends of the drum. The drum is fixed to a shaft 38 which extends outwardly through the side walls 37 and is rotatably supported in bearings 39 mounted upon the outer sides of the walls 37. The cylindrical outer surface of the drum is covered with wire bristles 40 which form a brush surface.

An electric motor 41 is mounted upon the base 1 beneath the mulling basin. Mounted upon the shaft of the motor is a sprocket wheel 42 which is connected by a driving chain 43 with a sprocket wheel 44 fixed to the diffusing drum shaft 38. 45 Another sprocket wheel 45 is also fixed to the shaft 38 and is connected by a drive chain 46 with a sprocket wheel 47 fixed to a muller drive shaft 48 located beneath the muller basin. The shaft 48 is supported by depending bearing brackets 49 mounted upon the underside of the bottom 4 of the basin. Fixed to the shaft 48 is a small driving pinion 50 which meshes with the relatively large beveled gear 51 mounted upon the muller shaft 10. The motor is thus adapted 50 to drive both the mulling rollers and the diffusing drum. A belt pulley 52 is also fixed to the drum shaft 39 and provides for the operation of the apparatus from a source of power other than the motor.

Mounted upon the base 1 of the apparatus is a centrifugal blower 52 which is adapted to be driven by the shaft 38, through a belt and pulley connection 53, 54, and 55. A pipe leads from the blower 52 to a discharge nozzle 56 located directly beneath the discharge opening 35 of the mulling basin. This nozzle has a width substantially equal to the length of the drum 36 and is directed outwardly through the brush portion substantially at a tangent to the upper side of 75

the drum. The blower is continuously operated by the motor or other source of power along with the rest of the apparatus, and directs a continuous blast of air through the brush upon the drum. This air blast dries the sand and assists its discharge from the diffusing drum.

In the operation of the apparatus the sand is delivered into the funnel-shaped hopper and passes through the opening 8 into the mulling basin. This opening is located so that it will deliver sand to the central area only of the basin, inwardly of the rollers 17 and 18. Usually the sand has been used for previous molds, and much of it is in a lumpy condition. The muller may and often is used to mix fresh batches of sand and clay, in which event the clay is added to the sand within the muller. The sand passing into the central portion of the basin is spread out by the rollers and worked along the bottom until it reaches the outer edge, being thoroughly mulled or kneaded on the way by the rollers, the loose sand A entrapped between the hard packed sand B which fills and extends above the concentric grooves 26 in the basin bottom remaining substantially stationary so that the bottom will not become abraded, all as explained hereinbefore. The rollers may be supported in a slightly elevated position so as not to bear too heavily upon the sand and interfere with its feed through the basin, for instance by means similar to what is illustrated in my prior patent, though even if no such elevating means is provided, the rollers will naturally swing, as the result of centrifugal force, upwardly from a position resting on the bottom and will be spaced from the bottom as shown in Figure 2. The sand worked to the outer portion of the basin and discharged through the opening 35 is delivered to the brush of the diffusing drum 36 at one side of the shaft, carried upwardly by the drum, subjected to the blast of air from the nozzle 56, and cast out into a hopper (not shown) at the opposite side of the shaft 36.

From the foregoing description and a study of the drawings it will be apparent that I have thus provided a simple and easily operated mulling device of rugged and durable construction which is adapted to operate continuously and efficiently for crushing or mulling and kneading sand mix-

tures and placing it in proper condition for use in making molds. It is believed that the construction, operation and advantages should be readily apparent to one skilled in the art without further explanation.

While I have shown and described the preferred embodiment of the invention, it should be understood that the disclosure is merely an exemplification of the principles involved as the right is reserved to make all such changes in the details of construction as will widen the field of utility and increase the adaptability of the device provided such changes constitute no departure from the spirit of the invention or the scope of the claims hereunto appended.

Having thus described the invention, I claim:

1. A sand mulling machine comprising a stationary mulling basin having a bottom and a side wall or rim, a shaft projecting upwardly through the bottom of said basin, a pair of axles 20 pivotally mounted on said shaft, a mulling roller mounted on each axle, said axles being of different lengths, said bottom being formed with grooves concentric with said shaft, means for rotating said shaft whereby said rollers are caused 25 to travel over the bottom of said basin, whereby sand will be collected and packed within said grooves, said sand acting to maintain a layer of unpacked sand immovable with respect to said packed sand during the operation of said rollers. 30

2. A sand mulling machine comprising a stationary mulling basin having a bottom and a side wall or rim, means within the basin for discharging the sand, a hopper at the top of the basin adapted to discharge sand thereinto, a 35 shaft projecting upwardly through the bottom of said basin, a pair of axles pivotally mounted on said shaft and on opposite sides of the center of said shaft, a mulling roller mounted on each axle, and means for rotating said shaft for causing said rollers to travel over the bottom of said basin to effect a sweeping action of the sand contained therein, said bottom of said basin being formed with concentric grooves within which sand may be packed by the action of the rollers, 40 said packed sand forming means to retain a layer of loose sand stationary with respect to said basin bottom during the travel of said rollers. 45

WILLIAM H. NICHOLLS.
